United States Patent Office.

CHRISTOPHER LIDREN, OF LAFAYETTE, INDIANA, ASSIGNOR TO HIMSELF
AND R. JACKSON, OF SAME PLACE.

Letters Patent No. 82,535, dated September 29, 1868.

IMPROVEMENT IN HARVESTERS.

The Schedule referred to in these Letters Patent and making part of the same.

TO ALL WHOM IT MAY CONCERN:

Be it known that I, CHRISTOPHER LIDREN, of Lafayette, in the county of Tippecanoe, and State of Indiana, have invented a new and improved Reaping and Mowing-Machine; and I do hereby declare that the following is a full, clear, and exact description thereof, which will enable those skilled in the art to make and use the same, reference being had to the accompanying drawings, forming part of this specification.

This invention relates to a new and improved reaping and mowing-machine, and it consists in a novel construction and arrangement of parts, as hereinafter fully shown and described, whereby several advantages are obtained over the ordinary machines in use.

In the accompanying sheet of drawings—

Figure 1, Sheet No. 1, is a side view of my invention, a portion being in section.

Figure 2, a plan or top view of the same.

Figure 3, a section of a portion of the same, taken in the line $x\ x$, fig. 2.

Figure 4, Sheet No. 2, a detached front view of the sickle-driving mechanism pertaining to the same.

Figure 5, a section of fig. 4, taken in the line $y\ y$.

Figure 6, a section of fig. 5, taken in the line $z\ z$.

Figure 7, a section of fig. 5, taken in the line $z'\ z'$.

Similar letters of reference indicate corresponding parts.

A represents the axle of the machine.

B the wheels thereof.

C the main frame, and

D the draught-pole.

The main frame C is simply a V-shaped bracket, the rear ends of which are fitted, by means of boxes $a\ a$, in grooves b , in the hubs c of the wheels B, the hubs being allowed to turn freely in the boxes, (see fig. 3.)

The hubs c are fitted loosely on the axle, but they are connected thereto, so as to revolve it when necessary, by means of ratchet-clutches E E, which are allowed to slide on the axle, and are connected thereto by a feather and groove, (see figs. 2 and 3.)

The boxes $a\ a$ are grooved to form lubricating-chambers $a\ a$, (see fig. 3,) to receive cotton-waste or other absorbent material, which is kept saturated with oil.

F is the driver's seat, the supports d of which are attached to the rear part of the main frame C, and in such a manner as to be capable of being adjusted further forward or backward, as may be desired.

The axle A projects considerably beyond the right-hand wheel B of the machine, and has two cams, G G', keyed firmly upon it at the outer side of said wheel B.

These cams may be described as wheels having their peripheries formed of a series of concaves, e, the centres of the concaves of one cam being opposite or in line with the points of junction of the concaves of the other cam, (see figs. 1 and 2.)

H represents an arm which is placed loosely on the axle A, between the two cams G G'.

This arm extends down below the cams, and upward as high as the tops thereof, the upper end of the arm being divaricated or forked, and having a box, I, attached to its prongs in such a manner that it may be adjusted higher or lower, as may be desired.

This is effected by means of bolts f, (see fig. 6,) which pass through vertical oblong slots g in the sides of the box, and fit in grooves in the upper ends of the prongs of the arm H, keys h being fitted in grooves in the inner surfaces of the sides of the box, and having their upper edges in contact with shoulders j on the prongs of the arm.

The bearings k of a rock-shaft, J, are just above the bolts f.

By this arrangement it will be seen that ample adjustment is obtained to compensate for wear of the jour-

nals of the rock-shaft and its bearings, and also of rollers $J \times J \times$, against which the cams $G G'$ act, said rollers being fitted on arms $l l$, which project laterally from the rock-shaft, at opposite sides.

These rollers, $J \times J \times$, have leather or other suitable material, m , fitted in their peripheries, and they are provided with oil-chambers n , by which they may always be kept properly lubricated, (see fig. 7.)

The leather, or other analogous material, m , obviates wear and tear, and diminishes friction.

It may be readily removed whenever required.

To the front end of the rock-shaft J , a bar or connecting-rod, K , is attached, the lower end of the latter being connected by a link, o , with the sickle L of the machine, said sickle being applied to a finger-bar, M , in the usual or any proper manner.

The operation of the sickle-driving mechanism will be readily understood.

As the machine is drawn along, and the clutches $E E$ adjusted so as to connect the hubs c of the wheels B with the axle A , the axle is made to rotate with said wheels, and the cams $G G'$, acting against the rollers $J \times J \times$, give a vibrating or oscillating movement to the shaft J , and a reciprocating motion is communicated from the latter to the sickle, through the media of the rod K and link o .

In order to render the sickle inoperative, all that is required is simply to adjust the clutches $E E$, so that the hubs c of the wheels will be disconnected from the axle A . The clutches are operated by the shipping-lever $E \times$.

The finger-bar M is attached to the lower end of the arm H by a universal joint, N , which admits of the finger-bar and sickle being raised and lowered according to the height of cut required; and as the arm H is fitted loosely on the axle A , it will be seen that the rod K is not interfered with in the least under this adjustment of the finger-bar and sickle.

To the inner end of the finger-bar M there is attached a shoe, O , the front end of which is connected by a universal joint, P , to a link, Q , the front end of the latter being connected to a crank, p , at one end of a shaft, R , at the front end of the main frame C .

The shaft R has a lever, S , secured to its inner end, and this lever is retained at any desired point within the scope of its movement, by means of a notched bar, q , the rear end of which is pivoted in the main frame.

This notched bar passes through a slot in the lever S , and engages with the latter, the lever being adjusted further forward or backward by raising the notched bar, through the media of a bent lever, r , and link s , shown clearly in fig. 1.

In order to admit of the finger-bar being raised longitudinally to clear or pass over obstructions, a curved bar, T , is attached to the lower end of the arm H , said bar T having an oblique position, so that when the lower end of the arm H is drawn forward, the bar T will come in contact with the inner end of the finger-bar, as shown at t , fig. 4, and retain or hold up the finger-bar horizontally.

U is the double-tree, the bolt u of which passes through an oblong slot, v , in the draught-pole D , the lower end of the bolt being connected, by a rod, w , with the lower end of the lever S , as shown in fig. 1.

By this arrangement the team is rendered subservient in raising the finger-bar.

I claim as new, and desire to secure by Letters Patent—

1. The combination of the hubs b , frame C , and clutches E , with the shipping-lever $E \times$, all these parts being arranged and constructed as herein shown and described.

2. The arrangement of the two cams $G G'$, axle A , forked arm H , box I , rock-shaft J , rollers $J \times$, and vibrating arm K , substantially as and for the purpose set forth.

3. The box I , attached to the arm H , and the rock-shaft J fitted therein, as shown, whereby proper adjustment may be made for the wear and tear of the rollers $J \times$, and the journals and boxes of the rock-shaft, substantially as set forth.

4. Constructing the rollers $J \times$ with oil-chambers n , and providing them with exterior surfaces of leather, m , or other suitable material, substantially as and for the purpose specified.

The above specification of my invention signed by me, this 25th day of March, A. D. 1868.

CHRISTOPHER LIDREN.
